(57) **CLAIM**

The ornamental design for a spacer for stacking multiple containers as shown and described.

DESCRIPTION

1. Spacer for stacking multiple containers

1.1: front view; 1.2: perspective front view of the right side;

1.3: perspective rear view; 1.4: perspective front view of the left side; 1.5: top view; 1.6: rear view; 1.7: side view of the left side; the bottom view is a mirror of the top view; the spacer for stacking multiple containers is used to stack multiple open containers upon each other.

The broken lines represent both parts of the spacer for stacking multiple containers as well as boundaries of the claim, wherein none of the broken lines form part of the claimed design.

1 Claim, 7 Drawing Sheets
